UNITED STATES PATENT OFFICE.

LOUIS F. W. MEESE, OF MINNEAPOLIS, MINNESOTA.

ADVERTISING-DISPLAYING MACHINE.

1,251,555.

Specification of Letters Patent.

Patented Jan. 1, 1918.

Application filed January 5, 1916. Serial No. 70,393.

To all whom it may concern:

Be it known that I, LOUIS F. W. MEESE, a citizen of the United States, residing at Minneapolis, in the county of Hennepin and State of Minnesota, have invented certain new and useful Improvements in Advertising-Displaying Machines; and I do hereby declare the following to be a full, clear, and exact description of the invention, such as will enable others skilled in the art to which it appertains to make and use the same.

My invention has for its object to provide a simple and efficient means for presenting to view, one after another, a plurality of display cards or sheets having marked thereon, various different printed matter or pictorial illustrations. Generally stated, the invention consists of the novel devices and combinations of devices hereinafter described and defined in the claims.

The improved machine is especially adapted and particularly intended for use to present to view, in succession, a multiplicity of different advertisements, but may be used for other analogous purposes, as, for example, a street or station indicator. A good many of the features of this invention are like those disclosed and claimed in my companion application, Serial Number 69,777, filed of date January 3, 1916, and entitled "Advertisement displaying machine". In the machine of said co-pending application, and in the present machine, the cards or sheets are marked with advertisement or other matter on both sides; but the said first machine involves means for presenting the cards to view in succession at the same sight opening or point of vision, with one side exposed and then with the other side exposed to view, whereas, in the present machine, the case or container has two sight openings, one in each side, and means is provided for presenting the cards, right side up, in succession, to view at one sight opening, to expose one side of the cards, and then, in succession, at the other sight opening, to present to view the other side of the cards.

In the accompanying drawings which illustrate the invention, like characters indicate like parts throughout the several views.

Referring to the drawings:

Figure 1 is a front elevation of the machine;

Fig. 2 is a vertical section taken on the line $x^2 x^2$ of Fig. 1;

Fig. 3 is a diagrammatic side elevation showing the card winding device and certain cooperating parts;

Fig. 4 is a fragmentary plan view showing one side of the machine, various parts being broken away;

Fig. 5 is a section taken approximately on the line $x^5 x^5$ of Fig. 4;

Fig. 6 is a section taken on the line $x^6 x^6$ of Fig. 5; and

Fig. 7 is a side elevation showing the lower portion of the case and certain of the operating gears.

The mechanism of the machine is placed within a rectangular case 1. In the present illustration, the sight openings are at 2 and are as large as the interior of the casing, but the said case might be provided with front and rear plates, both provided with suitable sight openings.

Mounted in suitable bearings on the sides of the case 1 is an upper shaft 3, fixed studs 4 and lower shafts 5 and 6. Secured on each of the said shafts and loosely journaled on each of the said studs are sprockets 7 arranged in laterally spaced sets of 4. A pair of laterally spaced parallel sprocket chains 8 run over the aligned laterally spaced sets of sprockets 7. The trunnions 4 are located higher than the shaft 3, and forwardly inclined channel-shaped tracks 9 extend from points above said trunnions to points considerably below said shaft 3. These tracks 9 are located quite close to the inner sides of the adjacent sprockets, and they are rigidly secured by brackets 10 secured thereto and to the sides of the case 1.

The front lower shaft 5, at one outer end carries a spur pinion 5^a that meshes with an intermediate spur pinion 11 journaled on the outside of the case. The intermediate pinion 11 meshes with a larger complete spur gear 12 journaled to the outer side of the case 1 and mounted to rotate with a large segmental spur gear 12^a, which latter intermittently engages a spur pinion 13 carried on the outer end of a transverse roller shaft 14^a that is journaled in the sides of the case 1 and carries a roller 14 that extends nearly, but not quite the entire distance between the laterally spaced chains 8. The laterally spaced chains 8 carry double-ended hooks or catch devices 15 and escape-

ment actuating cam lugs 16 that are arranged in laterally spaced pairs. The roller 14 carries, near its ends, a pair of hooks or catch devices 14^b. The functions of the elements 14^b, 15 and 16 will appear in the description of the operation.

The display cards 17 are flexible and may be made either of tough paper or of cloth, and at their upper and lower edges are provided with or secured to small rods 18 and 19 that project at their ends and are provided with wheel-like flanges 20 that are adapted to run in the channels of the inclined tracks 9. Normally, the upper rods 15 of the display cards are supported on the said tracks and they are permitted to escape one at a time, off from the lower end of the said tracks, by a duplex escapement mechanism comprising two escapement levers 21 pivoted to the sides of the case 1, by a small cross shaft 22. These escapement levers 21 are located just inward of the upper front sprockets 7 and they are provided with out-turned fingers 23 adapted to be engaged by the cam lugs 16 of the chains 8. The lower free ends of the escapement levers 21 are formed with reversely acting escapement pallets or teeth 24 and 25, the latter of which are bent inward and upward, to the inner sides of the lower ends of the inclined tracks 9. Normally, the pallets 24 engage the ends of the upper rod of the foremost display card and hold the same, and all of the other display cards, back upon the inclined tracks, as best shown in Fig. 5.

Operation: Let it first be assumed that the display cards are supported with their rods 18 uppermost and resting on the inclined tracks 9. When the cam lugs 16 come into engagement with the fingers 23 of the escapement levers 21, as shown in Fig. 2, the said levers will be raised, thereby causing the pallet 24 to release the foremost display card, and the pallets 25 will be in position to hold back the uppermost rod 18 of the second display card. When the first or foremost display card is thus released, the ends of its upper rod 18 will drop onto the lower prongs of the catch hooks 15 of the chains, and the ends of the lower rods 19 thereof will drop into position to be engaged by the catch hooks 14^b of the roller 14. At this time, the teeth of the segmental gear 12^a will engage the teeth of the pinion 13 and will cause the roller 14 to wind up the lower end portion of the flexible parts during the time which is required for the chains to carry the upper rod 18 past the said roller 14. As the said upper rod 18 is carried past the roller 14, the ends of the rod 18 slip from engagement with the front prongs into engagement with the rear prongs of the hooks 15, and, as these rear prongs carry the said rod and that end of the card onward, first toward the right

and then upward, the segmental gear passes out of mesh with the pinion 13 and thereby releases the roller 14 so that the card may be freely unwound therefrom. In this way, the card is first displayed at one side of the case with one face exposed and then is carried, the same end up, to the other side of the case where its other face is exposed. When the said card reaches the position shown by dotted lines in Fig. 2, its upper rod will drop off from the hooks 15 and onto the upper or receiving ends of the tracks 9 and will be delivered again to the lower ends of the said tracks and to the escapement devices, where it is released again. The escapement levers 21 may be operated by gravity alone, but, as shown, they are yieldingly pressed downward by gravity and by the action of light torsion springs 22^a anchored to the cross shaft 22 and to one side of the case 1.

What I claim is:

1. In a machine of the kind described, the combination with an endless carrier having means for carrying display cards with portions suspended therefrom, of a roller operative to wind up the suspended lower portions of the cards when the latter approach the same and to let the same out after the cards have moved past the same.

2. The combination with a case having sight openings at its opposite sides, of endless carrier belts working within said case and provided with means for carrying display cards with their lower portions suspended therefrom, of a take-up roller operative to wind up the suspended lower portions of said cards as the latter approach the same and to let the same out after the said cards have passed the same.

3. The combination with a case having sight openings at its opposite sides, of endless carrier belts working within said case and provided with means for carrying display cards with their lower portions suspended therefrom, of a take-up roller operative to wind up the suspended lower portions of said cards as the latter approach the same and to let the same out after the said cards have passed the same, and inclined tracks adapted to receive the cards from the upper portions of said belts and to deliver the same back to the said belts.

4. The combination with a case having sight openings at its opposite sides, of endless carrier belts working within said case and provided with means for carrying display cards with their lower portions suspended therefrom, of a take-up roller operative to wind up the suspended lower portions of said cards as the latter approach the same and to let the same out after the said cards have passed the same, and inclined tracks adapted to receive the cards from the upper portions of said belts and to deliver the same

the same back to the said belts, and escapement mechanism controlling the delivery of said cards, one at a time, from said tracks back onto said belts.

5. In a machine of the kind described, the combination with display cards having rods projecting from the sides of their upper and lower edges, of inclined tracks on which the uppermost rods of said display cards normally rest, endless carrier belts movable around said inclined tracks, hooks on said belts for receiving the ends of the upper rods as they pass from said tracks to said belts and operative to deliver the said 10 upper rods back onto said tracks, and an intermittently driven roller having hooks engageable with the lower rods of said cards to wind up the same while the cards are being rolled by said 15 belt toward said roller, but to release the same when the cards have been moved past the said roller.

20. 6. In a machine of the kind described, the combination with display cards having rods projecting from the sides of their upper and

lower edges, of inclined tracks on which the 25 uppermost rods of said display cards normally rest, endless carrier belts movable around said inclined tracks, hooks on said belts for receiving the ends of the upper rods as they pass from said tracks to said belts 30 and operative to deliver the said upper rods back onto said tracks, an intermittently driven roller having hooks engageable with the lower rods of said cards to wind up the same while the cards are being rolled by said 35 belt toward said roller, but to release the same when the cards have been moved past the said roller, and belt actuated escapement devices controlling the delivery of said cards from said tracks to the catch hooks of said 40 belts.

In testimony whereof I affix my signature in presence of two witnesses.

LOUIS F. W. MEESE.
